UNITED STATES PATENT OFFICE.

OTTO W. SIEBERT, OF WEST GARDNER, MASSACHUSETTS, ASSIGNOR TO
BAY STATE METAL WHEEL COMPANY, OF EAST TEMPLETON, MASSA-
CHUSETTS.

GO-CART.

SPECIFICATION forming part of Letters Patent No. 682,119, dated September 3, 1901.

Application filed June 22, 1901. Serial No. 65,573. (No model.)

To all whom it may concern:

Be it known that I, OTTO W. SIEBERT, of West Gardner, in the county of Worcester and State of Massachusetts, have invented 5 certain new and useful Improvements in Go-Carts, of which the following is a specification.

This invention has for its object to provide simple and effective means for adjusting the hinged back and dasher of a go-cart and holding said parts in their raised and depressed 10 positions.

The invention consists in the improvements hereinafter described and claimed.

Of the accompanying drawings, forming a 15 part of this specification, Figure 1 represents a side elevation of a go-cart embodying my invention, the back being raised and the dasher lowered. Fig. 2 represents a side view showing the back lowered and the dasher 20 raised. Fig. 3 represents a side elevation showing both the back and the dasher raised. Fig. 4 represents a rear elevation, on a larger scale, showing parts of the seat and back and of the adjusting and locking mechanism. Fig. 25 5 represents a section on line 5 5 of Fig. 4. Fig. 6 represents a section on line 6 6 of Fig. 4. Fig. 7 represents a view similar to Fig. 5, showing the back-supporting strut in a different position. Figs. 8 and 9 are views similar to a part of Fig. 5, showing the back-supporting strut in different positions. Fig. 10 represents a section on line 10 10 of Fig. 4.

The same reference characters indicate the same parts in all of the figures.

In the drawings, *a* represents the seat or bottom of a go-cart body, *b* represents the back, which is hinged at *c* to the rear end of the seat, and *d* represents the dasher, which is hinged at *e* to the front end of the seat. These 35 parts and the side portions of the body may be of any suitable form and construction. The back is supported either in the raised position (shown in Figs. 1 and 3) or in the depressed position (shown in Fig. 2) by means 40 of a strut *f*, journaled in a bearing *g* on the upper portion of the back, and a locking member *h*, supported by a bracket *i*, which is affixed to and projects rearwardly from the seat. The locking member *h* is pivoted to the bracket 45 *i* by means of trunnions *h'* on the ends of the locking member, said trunnions entering socket-

ets in the bracket, which is shown in Figs. 6 and 7 as having two side portions between which the locking member is located. In the locking member is formed a slot *h*², extending lengthwise of said member. The lower portion of the strut *f* is flattened and formed to slide in the slot *h*² when the strut is turned to the position shown in Fig. 7. The flattened portion of the strut is provided with two pairs 55 of notches *f'*, arranged at different heights, said notches being formed to engage the locking member when the strut is turned crosswise thereof, as shown in Fig. 6. The upper portion of the strut is cylindrical and is adapted 60 to rotate in the bearing *g* to cause the flattened portion to assume the positions shown in Figs. 6 and 7. The said bearing has two contracted end portions *g' g'*, fitting the cylindrical portion of the strut, and an enlarged central portion forming a casing or chamber *g*², Fig. 5, in which is located a collar *f*², affixed to the strut, said collar abutting against the contracted portions of the bearing and preventing endwise movement 70 of the strut in the bearing. A helical spring *j*, surrounding the collar *f*², has one end *j'* engaged with an ear on said collar, its other end *j*² bearing on the casing. The tendency of 75 said spring is to rotate the strut in the direction indicated by the arrow in Fig. 7, thus causing it to normally assume the position shown in Fig. 6, in which position it is arrested against further rotation by stop-shoulders *h*³, formed on the locking member *h*. 80 When the back is raised, the lower notches in the strut are in position to engage the locking member, and when the back is lowered the upper notches are in position to engage 85 said member. When the back is to be moved 90 from one position to the other, the strut is turned to the position shown in Fig. 7 and is then free to slide in the locking member, the spring turning the strut into engagement 95 with the locking member when the desired notches *f'* coincide therewith. The pivotal connection between the locking member and the bracket *i* enables the locking member to conform to the various inclinations of the strut, as shown in Figs. 8 and 9, Fig. 8 showing the position of the strut when the back is raised and Fig. 9 when the back is de- 100

pressed. The upper end of the strut is provided with a handle f^3 , by which it may be turned against the force of the spring.

k k' represent toggle-links, the outer ends 5 of which are jointed, the one to an ear on the dasher and the other to a bracket m , projecting downwardly from the front portion of the seat. When said links are straightened, as shown in Figs. 2 and 3, they support the 10 dasher in a raised position, and when they are thrown out of alignment the dasher falls to the position shown in Fig. 1. I provide means whereby the toggle-links may be straightened to raise the dasher either by the 15 depression of the back b or independently thereof. Said means comprise a lever n , pivoted at n' to the rear bracket i , a rod o , connecting the lever n with the toggle-link k , a collar p , fitted to slide on the cylindrical portion 20 of the strut f , (said portion being adapted to turn in the collar,) and a rod q , connecting the collar p with the lever n . When the back is raised and the dasher lowered, as shown in Fig. 1, the collar p is supported in 25 contact with or in close proximity to the strut bearing g , so that when the back is swung downwardly said bearing will force the collar p and rod q downwardly, thus moving the lever n , rod o , and toggle-links k k' to the 30 positions shown in Fig. 2 and raising the dasher. When the parts are in this position, a toe k^2 on the lower end of the toggle-link k' bears on the rod o , which prevents further forward movement of the meeting ends of 35 the links, and thus locks the links in their dasher-supporting position. The back may now be raised without affecting the dasher, the bearing g being separated from the collar p by the upward movement of the back, as 40 shown in Fig. 3. Hence the back and dasher may be held in their raised positions simultaneously. The dasher may be lowered without lowering the back by moving the rod o backwardly, and thus breaking the toggle- 45 joint. This may be accomplished by a direct backward pull on the rod o , which may have its rear end o' bent to form a hook or handle adapted to be engaged by the foot or hand of the operator. The same result may be ac- 50 complished by an upward pull on the collar p or rod q , the collar being in either case raised to contact with the strut-bearing g , so that the next depression of the back will raise the dasher. The dasher may, however, be 55 raised without depressing the back by a forward push on the rod o or by a downward push on the collar p or rod q .

It is obvious that the depression of the collar p may be effected by a collar or enlargement 60 on the strut instead of by the bearing g . In other words, the bearing g may be considered as a shoulder or enlargement which moves with the strut to depress the collar when the back is being depressed.

65 I claim—

1. A go-cart comprising a seat, a hinged back, a strut journaled in a bearing on the

upper portion of the back, and having notches arranged at different heights, said strut being adapted to assume different positions by partial rotative movements in said bearing, a locking member supported behind the seat and having a strut-receiving slot, said locking member being formed to engage a notched portion of the strut when the latter is in one 70 of said positions, and to permit the endwise movement of the strut in the slot when the strut is in another position, and a spring engaged with the strut and adapted to normally hold it in engagement with said locking member. 80

2. A go-cart comprising a seat, a hinged back, a spring-controlled strut rotatively connected with the back and provided with notches arranged at different heights, and a locking device formed to engage notched portions of the strut and having a slot in which the strut is movable endwise, said locking device being pivotally connected to a support on the seat, so that it accommodates itself to 90 varying inclinations of the back and strut.

3. A go-cart comprising a seat, a hinged back, a spring-controlled strut rotatively connected with the back and provided with notches arranged at different heights, and a locking device formed to engage notched portions of the strut and having a slot in which the strut is movable endwise, said locking device being pivotally connected to a support on the seat and provided with stops which 100 limit the rotation of the strut by its spring.

4. A go-cart comprising a seat, a hinged back, a bearing attached to the upper portion of the back and having contracted ends and an intermediate enlargement, a strut journaled in said contracted ends and having notches located at different heights, and a collar located in said enlargement, said collar abutting against the reduced ends of the bearing and preventing endwise movement of the 105 strut, a locking device formed to engage notched portions of the strut, and having a slot in which the strut is movable endwise.

5. A go-cart comprising a seat, a bracket affixed to the seat and extending rearwardly 115 therefrom, a locking member pivoted to said bracket and provided with a strut-receiving slot and with stop-shoulders adjacent to the slot, a hinged back, a strut journaled in a bearing on the upper portion of the back and extending downwardly therefrom through the slot in the locking member, said strut having notches arranged at different heights and formed to engage the locking member, and a spring engaged with the strut and with its 125 bearing and adapted to normally hold the strut in engagement with the locking member.

6. A go-cart comprising a seat, a hinged back, a hinged dasher, a strut engaged with the back, a locking member supported behind 130 the seat, said strut and locking member co-operating in supporting the back in different positions, a bearing or enlargement affixed to and movable with the strut, and dasher ele-

vating and supporting mechanism comprising a collar having a sliding connection with the strut and located below said enlargement, so that it may be depressed by the latter, and 5 connections between said collar and the dasher, whereby the dasher may be raised either by the depression of the back or independently thereof.

7. A go-cart comprising a seat, a hinged 10 back, a back-supporting strut journaled in a bearing on the upper portion of the back and extending downwardly therefrom, means supported by the seat for locking said strut and supporting the back in different positions, a 15 hinged dasher, toggle-links jointed at their outer ends to the dasher and to a bracket affixed to the seat and adapted when straightened to support the dasher in a raised position, and toggle-straightening devices includ- 20 ing a collar slidably connected with the strut below the strut-bearing and connections between said collar and the toggle-links whereby when the back is depressed the strut-bearing or its specified equivalent depresses the 25 collar and causes the latter through said toggle-links and intermediate connections to

raise the dasher, the sliding connection between the strut and collar permitting the back to be raised without lowering the seat.

8. A go-cart comprising a seat, a hinged 30 back, a hinged dasher, a rear bracket extending rearwardly from the rear portion of the seat, a front bracket extending downwardly from the front portion of the seat, a spring-controlled strut journaled in a bearing on the 35 upper portion of the back and extending downwardly therefrom, a locking member pivotally connected with the rear bracket and adapted to lock the strut and back in different positions, toggle-links jointed at their 40 outer ends to the dasher and front bracket respectively, a lever pivoted to the rear bracket, a collar fitted to slide on the strut below the strut-bearing, a rod connecting said lever with one of the toggle-links, and an 45 other rod connecting the lever with the collar.

In testimony whereof I have affixed my signature in presence of two witnesses.

OTTO W. SIEBERT.
